(57) **CLAIM**

The ornamental design for a combination optical sight and accessory mount, as shown and described.

DESCRIPTION

FIG. 1 is an isometric view of a combination optical sight and accessory mount showing my new design;

FIG. 2 is another isometric view of the combination optical sight and accessory mount of FIG. 1;

FIG. 3 is a front elevational view of the combination optical sight and accessory mount of FIG. 1;

FIG. 4 is a right side elevational view of the combination optical sight and accessory mount of FIG. 1;

FIG. 5 is a rear elevational view of the combination optical sight and accessory mount of FIG. 1;

FIG. 6 is a left side elevational view of the combination optical sight and accessory mount of FIG. 1;

FIG. 7 is a top plan view of the combination optical sight and accessory mount of FIG. 1; and,

FIG. 8 is a bottom plan view of the combination optical sight and accessory mount of FIG. 1.

The broken lines represent portions of the combination optical sight and accessory mount that form no part of the claimed design.

1 Claim, 7 Drawing Sheets
